REFRIGERATION

Justice H. Beach, Canton, Ohio, assignor to The
Hoover Company, North Canton, Ohio

Application October 3, 1940, Serial No. 359,482

12 Claims. (Cl. 62—5)

This application relates to the art of refrigeration and more particularly to a novel arrangement of refrigerating mechanism and control system so constructed and arranged that variable temperatures may be provided in a compartment for the purpose of freezing ice, desserts, etc. while maintaining a substantially constant temperature in the main foodstuffs refrigerating chamber all with the same cooling unit.

It is a common objection to present refrigerating machines that necessary variations in the evaporator temperatures to control the rate of ice production or to freeze desserts at a desired rate concomitantly produces objectionable variations in the temperature of the foodstuffs storage compartment causing an undesirable drying and even freezing of the foodstuffs under some conditions of operation and allowing the temperature of the refrigerating compartment to exceed safe food storage values under other conditions of operation.

Accordingly, it is an object of the present invention to provide a refrigerating mechanism which overcomes the above mentioned difficulties of present machines.

More specifically, it is an object of the present invention to provide a cooling unit comprising freezing chamber and air cooling parts in which part of the air cooling load is carried by the freezing chamber and in which a control mechanism is provided which simultaneously operates to regulate the temperature control points of the cooling unit and to regulate the air flow thereacross in order to provide variable temperatures of the cooling unit while maintaining a substantially constant refrigerating effect for the food storage chamber.

Various other objects and advantages of the invention will become apparent as the description proceeds when taken in connection with the accompanying drawings in which:

Figure 1 is a partially diagrammatic and partially sectional view of an absorption refrigerating mechanism embodying the present invention.

Figure 2 is a perspective view drawn to an enlarged scale of the cooling unit utilized in connection with the invention, and

Figure 3 is a perspective view drawn to an enlarged scale of the cooling unit, freezing chamber housing and control mechanism.

Referring now to the drawings in detail and first to Figure 1 thereof, there is illustrated an absorption refrigerating mechanism of the three-fluid type comprising a boiler B, an analyzer D, an air-cooled rectifier R, a tubular air-cooled

condenser C, an evaporator E, a gas heat exchanger G, an inclined tubular air-cooled absorber A, a liquid heat exchanger L, a solution reservoir S, and a gas circulating pump F which is driven by a suitable electrical motor M. These elements are suitably connected by various conduits to form a plurality of gas and liquid circuits constituting a complete refrigerating mechanism. The boiler B is heated by a suitable fluid 10 fuel burner H which is controlled by a solenoid valve V.

The above described refrigerating system will be charged with a suitable refrigerant, such as ammonia, a suitable solvent therefor, such as water, and an inert pressure equalizing medium, preferably a dense inert gas like nitrogen.

The boiler-analyzer, absorber, liquid heat exchanger and solution reservoir S are connected by suitable conduits as illustrated to form an absorption solution circuit. Weak solution from the boiler B is conveyed to the upper portion of the absorber A by way of the conduit 11, liquid heat exchanger L, conduit 12, solution reservoir S, and gas lift circulating pump 13. The gas lift pump circulating conduit 13 discharges into the suction conduit 14 of the circulating fan F and the upper portion of the reservoir S is vented by means of a conduit 15 to the conduit 14. Pumping gas is conveyed from the discharge conduit 16 of the circulating fan to the gas lift pump 13 by means of the conduit 17. Enriched solution is conveyed from the bottom portion of the absorber to the analyzer D by way of the conduit 18, liquid heat exchanger L and the conduit 19. 20 The refrigerant vapor evolved in the boiler-analyzer is conveyed from the upper portion of the analyzer to the upper portion of the condenser C by way of the conduit 20 which includes the rectifier R.

25 The lean inert gas which is drawn from the upper portion of the absorber through the conduit 14 to the circulating fan is conveyed therefrom to the bottom portion of the evaporator E by way of the conduit 16, gas heat exchanger G and evaporator gas supply conduit 22. After traversing the evaporator the resulting rich inert gas is then conveyed to the bottom portion of the absorber A by way of the conduit 23, gas heat exchanger G, and the conduit 24.

30 The refrigerant vapor condensed in the condenser C is conveyed therefrom to the evaporator gas inlet conduit 22 at the bottom portion of the evaporator by means of the conduit 26 and the U-shaped conduit 27. The condenser side of the U-shaped conduit 27 is vented by means of a con-

duit 28 to the rich gas side of the gas heat exchanger G.

As is more clearly shown in Figure 2, the evaporator E comprises a plurality of substantially horizontal parallel and vertically spaced coil sections 30 which are serially connected by the riser conduits 31 and 32. The gas supply conduit 22 connects the lowest of the horizontal sections 30. The highest of the sections 30 connects to a vertically extending coil section 35 which is positioned vertically in the rear of the coil section 30. The bottom portion of the coil section 35 then connects directly to the rich gas discharge conduit 23.

The bottom portion of the coil 35 is drained by means of a conduit 36 which includes a U-shaped liquid trapping portion to a drain conduit 37 which connects between the top portion of the bottom coil section 30 on the rich gas side of the gas heat exchanger G as is shown in Figure 1.

The evaporator E is of the type in which the inert gas is propelled through the evaporator with a velocity and pressure sufficient to sweep or drag the liquid refrigerant therethrough by the frictional drag of the inert gas stream flowing in contact with the liquid. This insures positive distribution of the liquid through all portions of the evaporating conduit. It should be noted that the liquid refrigerant and inert gas traverse the freezing coils 30 in their entirety before reaching the vertically extending coil 35.

The evaporator E, with the exception of the vertically extending coil 35 and the gas connecting conduits 22 and 23, is encased within a housing 40 which is provided with a movable door 41. Suitable tray supporting shelves 42 overlie the bottom and intermediate coils 30 to form supports for ice freezing trays. The side walls 44 of the casing 40 extend rearwardly, as is clearly shown in Figure 3, to a distance sufficient to extend beyond the coil section 35 and the fins 45 mounted thereon as shown in Figure 1.

Referring now to Figure 1, the apparatus is assembled with a cabinet construction 46 which is provided with a food compartment 47. The rear wall of the cabinet 46 is provided with an opening 48 which is designed to be closed by an insulated panel 49 and a sealing gasket 50. The refrigerating mechanism, the evaporator casing and the panel 49 are assembled outside the cabinet assembly. The refrigerating mechanism and the panel 49 are then assembled with the cabinet as a unit simply by sliding the cooling unit through the opening 48 and the panel 49 into the opening 48 after which the sealing gasket 50 is placed in position.

As may readily be seen from Figure 1, the rearwardly extending wings on the side walls 44 of the cooling unit abut the inner face of the panel 49 to form an open ended channel housing the vertically extending coil 35 and the fins 45 mounted thereupon, thus forming a flue for air circulating within the compartment 47.

The apparatus is provided with a suitable control mechanism 60 which is mounted upon the outside face of the panel 49 and at the upper portion thereof. This mechanism may be of any desired type, for example that illustrated and described in the application of Curtis C. Coons, Serial No. 148,424, filed June 16, 1937, now Patent No. 2,228,343, dated Jan. 14, 1941, and application of Arnold D. Siedle and William H. Kitto, Serial No. 160,274, filed August 21, 1937, now Patent No. 2,262,656, dated November 11, 1941, or the control mechanism 60 may simply consist of

a thermostatic switch operated to respond to the temperature of the bottom evaporator coil E by means of the control bulb 61 which is connected to the bellows within the element 60 by means of capillary conduits 62. A suitable adjusting shaft 63 extends from the control mechanism 60 through the panel 49 and across the top of the casing 40 where it terminates in a control knob 64 mounted in front of an indica bearing panel 65. The control mechanism 60 is connected to a suitable source of electrical energy by means of a conductor 66 and to the circulating motor M by means of a conductor 67. The circulating motor M and the solenoid control valve V for the burner H are connected by means of a conductor 68 and the solenoid valve V then connects to a source of electrical energy by means of a conductor 69, thus completing the electrical circuit. When the thermostatic mechanism operates to complete the circuit between the conductors 67 and 66, the circulating motor M is placed in operation and the valve V is energized and moved to open position, thus placing the apparatus in operative condition.

Adjustment of the knob 64 determines the temperature carried on the evaporator; that is, it adjusts the control point of the thermostatic switching mechanism 60.

The upper end of the flue housing the box-cooling coil 35 is arranged to be controlled by movably mounted dampers 70 which are journaled in ears 71 formed on the side walls 44 of the casing 40. The dampers 70 are operated by a pair of spiral beveled gears 72, one of which is rigidly mounted upon the shaft 63 and the other of which is journaled with and rigidly attached to the dampers 70. Consequently rotation of the adjusting dial knob 64 not only regulates the control point of the evaporator E but also adjusts the position of the dampers 70.

The operation of the invention is as follows: For every given control point for which the thermostatic mechanism 60 may be set the housing 40 has a definite capacity for maintaining safe refrigerating temperatures within the compartment 47. However, this capacity is insufficient to maintain the load within the compartment 47 except when the element 64 has adjusted the control mechanism 60 to maintain the lowest possible temperature at the evaporator E which would correspond for example to a very fast freezing rate for freezing desserts and the like. On the other hand, the combination of the box-cooling capacity of the casing 40 and the coil 35 is too great for the load except when the temperature of the evaporator E is set at its highest normal operating figure. Therefore, the spiral bevel gears 72 and dampers 70 are so arranged that the damper 70 is in the full line position, shown in Figure 1, that is, in position completely to prevent air flow across the coil 35 when the dial 64 has been adjusted for the lowest temperature setting of the thermostatic mechanism and the damper 70 will assume the vertical position indicated in dotted lines in Figure 1; that is, the complete open position for the flue housing the coil 35 when the knob 64 has been adjusted to the highest normal operating temperature condition. In between these two extremes the damper 70 will assume various positions between the full and dotted line positions illustrated in Figure 1 to provide various throttling effects upon the air stream flowing across the coil 35. As a consequence of this arrangement the refrigerating effect produced

within the compartment 47 is maintained substantially constant at some pre-selected optimum value, as a result of which foodstuffs are neither in danger of freezing nor are they in danger of deterioration because of too high a temperature being carried within the compartment 47.

The present invention provides a means by which the box-cooling load is proportioned in various ratios between the finned coil 35 and the freezing chamber casing 40 at varying temperature settings of the thermostatic control mechanism. Therefore, a single cooling unit is provided which is so arranged as to carry varying temperature conditions within the freezing chamber and to maintain substantially constant temperature conditions within the storage compartment under all conditions of operation.

While the invention has been described and illustrated in detail, various changes may be made in the arrangement, construction and proportion of parts without departing from the spirit of the invention or the scope of the appended claims.

I claim:

1. Refrigerating apparatus comprising a refrigerating chamber, a cooling unit in said chamber, control means for setting the effective temperature carried by said cooling unit and means operated by said first mentioned means for controlling the circulation of air across said cooling unit to maintain optimum refrigerating conditions in said chamber.

2. Refrigerating apparatus comprising a refrigerating chamber, a cooling unit in said chamber comprising a refrigerating compartment and an air cooling coil, control means for setting the effective temperature carried by said cooling unit, and means operated by said first mentioned means for controlling the circulation of air across said cooling unit to maintain optimum refrigerating conditions in said chamber.

3. Refrigerating apparatus comprising an insulated refrigerating chamber, a cooling unit including a freezing compartment and an air cooling element positioned within said chamber, means for supplying a cooling medium to said cooling unit, thermostatic means for controlling the supply of cooling medium to said cooling unit in response to the temperature thereof, means for controlling the effective air flow across said air cooling element, and a manually operable control knob and associated motion transmitting means for adjusting said thermostatic means and said air flow control means to regulate the temperature of said compartment and the temperature of said chamber.

4. Refrigerating apparatus comprising an insulated refrigerating chamber, a cooling unit including a freezing compartment and an air cooling element positioned within said chamber, means for supplying a cooling medium to said cooling unit, thermostatic means for controlling the supply of cooling medium to said cooling unit in response to the temperature thereof, damper means for controlling the flow of air across said air cooling element, and manually operable means for simultaneously adjusting said damper means and the control point of said thermostatic means.

5. In a refrigerating apparatus an insulated chamber having an opening in one wall thereof, a refrigerating mechanism associated with said chamber comprising a freezing housing, a cooling unit including a portion within said housing and an air cooling portion, a closure element for the opening in the wall of said housing carried

by said refrigerating mechanism, control mechanism for said refrigerating mechanism, manually adjustable means for regulating the control point of said control mechanism, and means for regulating the flow of air across the air cooling portion of said cooling unit constructed and arranged to be operated by said manually adjustable means.

6. Refrigerating apparatus comprising an insulated refrigerating compartment having a cooling unit receiving opening in its rear wall, refrigerating apparatus associated with said compartment comprising a cooling unit having a freezing portion and an air cooling portion within said compartment, a closure element for said opening, a housing enclosing the freezing portion of said cooling unit, the air cooling portion of said cooling unit being positioned between the rear wall of said housing and said closure element, rearwardly extending flanges on said housing arranged to form an open ended air flue housing the air cooling portion of said cooling unit, control mechanism for said cooling unit, damper means for controlling the flow of air through said flue, and manually operable means for regulating said control means and said damper means.

7. Refrigerating apparatus comprising an insulated refrigerating compartment having a cooling unit receiving opening in its rear wall, refrigerating apparatus associated with said compartment comprising a cooling unit having a freezing portion and an air cooling portion within said compartment, a closure element for said opening, a housing enclosing the freezing portion of said cooling unit, the air cooling portion of said cooling unit being positioned between the rear wall of said housing and said closure element, rearwardly extending flanges on said housing arranged to form an open ended air flue housing the air cooling portion of said cooling unit, thermostatic means responsive to the temperature of said cooling unit arranged to control the refrigerating effect thereof, said thermostatic means being mounted upon said closure element on the exterior thereof, a damper mounted on said housing to open or close said air flue, an adjusting knob mounted at the front of said housing, and a rigid motion transmitting means operably connecting said knob to said means and to said damper.

8. Refrigerating apparatus including an evaporator having a plurality of serially connected freezing coils and an air cooling coil, means for circulating an inert gas through said evaporator in a direction to traverse said freezing coils prior to traversing said air cooling coil with a velocity and pressure sufficient to circulate refrigerant liquid through said evaporator, means for supplying refrigerant liquid to said evaporator to be circulated by said inert gas as it is evaporating, means responsive to the temperature of said evaporator for controlling the operation thereof to maintain a predetermined temperature, means for adjusting said evaporator temperature responsive means to select the value of said predetermined temperature, and means operated by said adjusting means for governing the effective air flow across said evaporator.

9. Refrigerating apparatus comprising an insulated refrigerating compartment, a freezing receptacle support in said compartment, a chilling unit having a part arranged to refrigerate said support and another part arranged to refrigerate the air in said compartment, control means for

regulating the temperature setting of said chilling unit, means for governing the circulation of air over said air refrigerating part of said chilling unit, and common means for regulating each of said means to decrease air flow past said chilling unit as the temperature setting thereof is reduced and to increase air flow past said chilling unit as the temperature setting thereof is increased.

10. Refrigerating apparatus comprising a cabinet structure, a cooling unit in said cabinet structure having a freezing portion and an air cooling portion provided with an extensive heat transfer surface, a casing around said freezing portion, means for supplying a refrigerant medium to said cooling unit, control means arranged to respond to the temperature of said freezing portion for controlling said refrigerant medium supply means, means for governing the circulation of air in heat exchange relation with said air cooling portion, a manually operable regulating device, and means for transmitting movement of said regulating device to said control means to regulate the control point thereof and to said air circulating governing means to decrease circulation of air in heat exchange relation with said air cooling portion as the control point of said control means is lowered.

11. Refrigerating apparatus comprising an insulated refrigerating compartment, a refrigerating mechanism including a cooling unit having a freezing portion and an air cooling portion in said refrigerating compartment, means forming a freezing housing around said freezing portion of said cooling unit, control means for regulating the temperature of said chilling unit, damper means for regulating the flow of air in heat exchange with said air cooling portion of said cooling unit, and actuating means for simultaneously adjusting said control means and said damper means.
12. Refrigerating apparatus comprising an insulated refrigerating compartment, a refrigerating mechanism including a cooling unit in said refrigerating compartment having an air cooling element, adjustable control means for regulating the temperature of said cooling unit, means for regulating the flow of air in heat exchange relation with said air cooling means, and adjusting means for simultaneously adjusting said control means to alter the temperature setting of said cooling unit and to operate said regulating means to vary the flow of air in heat exchange relation with said cooling unit.

JUSTICE H. BEACH.
